(57) **CLAIM**

The ornamental design for a lighting module wide distribution lens, as shown and described.

DESCRIPTION

FIG. 1 is a top, perspective view of a lighting module wide distribution lens in accordance with the present design; FIG. 2 is a bottom, perspective view of the lighting module wide distribution lens of FIG. 1, illustrating a heatsink (shown in broken lines) received by the lighting module wide distribution lens;

FIG. 3 is a front view of the lighting module wide distribution lens of FIG. 1, shown increased in scale for clarity; FIG. 4 is a rear view of the lighting module wide distribution lens of FIG. 1, shown increased in scale for clarity; FIG. 5 is a left, side view of the lighting module wide distribution lens of FIG. 1;

FIG. 6 is a right, side view of the lighting module wide distribution lens of FIG. 1;

FIG. 7 is a top view of the lighting module wide distribution lens of FIG. 1; and,

FIG. 8 is a bottom view of the lighting module wide distribution lens of FIG. 1.

The broken lines provided in the drawings form no part of the claimed design.

1 Claim, 4 Drawing Sheets
